UNITED STATES PATENT OFFICE.

WILLIAM SEVERNS, OF CHICAGO, ILLINOIS.

METHOD OF MAKING MOPS.

Application filed August 17, 1921. Serial No. 493,012.

To all whom it may concern:

Be it known that I, WILLIAM SEVERNS, a citizen of the United States, and a resident of the city of Chicago, in the county of Cook and State of Illinois, have invented certain new and useful Improvements in a Method of Making Mops; and I do hereby declare that the following is a full, clear, and exact description of the same, reference being had to the accompanying drawings, and to the numerals of reference marked thereon, which form a part of this specification.

This invention relates to an improved method and process of making mops and to the apparatus for use in connection therewith and has for one of its objects the manufacture of a mop such as is used for cleaning and polishing floors. This process is intended to eliminate the waste which ordinarily resulted from the manufacture of such mops. As usually made, these mops were composed of a plurality of strands of some suitable material such as cotton yarn or the like, of equal length and bound together at the top by a band of cloth, canvas, or some flexible material which sometimes has inserted therethrough for reinforcement a strip of some suitable metal which is afterwards bent into any desired shape. A handle is affixed thereto for the purpose of ready manipulation.

Ordinarily in the manufacture of these mops a plurality of strands of yarn or the like cut to approximately the required length were thrown in a heap from which the operator collected a number of these strands and laid them transversely upon a strip of cloth, to which they were afterwards sewed by machine or by hand and the strip was then folded along its middle longitudinal line and again sewed, leaving an open space for the insertion of the reinforcing strip if used. After the strands were all sewed to the strip they were cut off evenly on the ends to make a finished job, which necessarily resulted in a good deal of waste and loss of material, which being in small pieces was not useful in any way and was thrown away resulting in a great deal of loss.

One of the objects therefore of this invention is the provision of a method for manufacturing such cleaning and polishing mops whereby the strands are secured evenly on the canvas with their ends in exact alignment so that there will be no necessity of

trimming the same to make a finished product.

Another object of this invention is the provision of a method of making mops or the like wherein the strands composing the mop are all arranged evenly together in proper alignment and so spaced from each other that there will be no possibility of any uneven lumps or the like forming in the mop, and that therefore the wear on the same will be equally distributed at all parts thereof.

Another important object of this invention is the provision of a method for making mops or the like which shall be much more efficient and rapid and adapted to turn out the same with a minimum of work and expense, whereby the mops may be produced more cheaply and in larger quantities, which method also results in the construction of a much better appearing article or finished product.

Still another important object of this invention is the provision of an improved apparatus for carrying out this new process which shall be simple of construction and not liable to get out of order.

Other and further important objects of the invention will be apparent from the disclosures in the accompanying drawings and the following specification.

The invention (in a preferred form) is illustrated in the drawings and hereinafter more fully described.

On the drawings:

Figure 1 is a perspective view of a frame having a plurality of layers of yarn wound thereupon in regular order which yarn is subsequently made into a mop by the improved process of this invention.

Figure 2 shows the frame having the yarn wound thereupon and with the binding strips which form the top of the mop shown sewed in position upon the yarn, one of the strips being on each side, or with one strip passing entirely therearound, as desired.

Figure 3 is a sectional view showing the frame in position upon a cutting machine which separates the yarn along two desired lines.

Figure 4 is a perspective view showing the yarn or swatch removed from the frame and doubled over into the form of a mop.

Figure 5 is a side elevation of the finished mop showing the finishing stitches therein and the reinforcing member.

As shown on the drawings:

The reference numeral 10 indicates a frame made of wood, metal or any other suitable material upon which the yarn is wound in the form shown in the Figures 1 and 2, this regular arrangement of the strands being accomplished in any desired manner, preferably by fixing the frame 10 in a machine which revolves the same about its longitudinal axis and collects the yarn from one or more reels, spools or cones as preferred. Depressions 12 are provided in the end members of the frame 10 adapted to be connected to the spindle of the winding machine which revolves the frame 10. The sides 14 of the frame 10 may be formed with slots at the ends thereof for the reception of the end members of the frame which are held in position in any suitable manner. The outer edges of the side members 14 are grooved to accommodate the cutting edges of circular knives 16 which are mounted upon vertical shafts 18 in bearings 20 in a cutting machine of any desired form, that shown in Figure 3 being one convenient type.

This machine is provided with driving and loose pulleys 22 and 24 respectively, mounted on an axle or shaft 26 which has keyed thereon for sliding but not rotating movement beveled gears 28 and 30 respectively co-operating with gears 32 and 34 mounted on the ends of the shafts 18. These gears 32 and 34 are adapted to rotate the circular knives 16 in opposite directions simultaneously, as will be evident from an inspection of Figure 3. The knives are adjustable to and from each other to accommodate frames of different widths.

40 The operation is as follows:

Yarn 11 is wound from the skein in an even manner upon the rectangular frame 10 usually by rotating the frame by any means suitable for the purpose, usually a winding machine, to which it is engaged by the notches 12 in the end members of the frame 10. After a predetermined weight or quantity of yarn 11 has been wound upon the frame 10 to make the mop, the frame is removed from the machine and binding strips 36 of canvas or other suitable material sewed on the yarn in any suitable manner. A strip of canvas of suitable width and in length preferably slightly more than twice that of the length of the mop to be constructed is placed around the winding on each side thereof with the longitudinal center of the strip along the axis of the reel, and stitched through and through, as shown in Figure 2, and after the stitches are passed therethrough the whole will present an appearance as shown in Figure 2. The binding strip 36 is sewed upon the strands of yarn assembled in even relation on the frame 10 by any suitable

means, such as a machine provided for the purpose or by hand if desired.

After the binding strips 36 have been securely sewed in position the frame 10 with the yarn 11 thereon is passed through a cutting machine, as shown in Figure 3, and the strands of yarn severed along the edges of the side members 14 by the knives 16, the edges of these knives co-operating with the grooves in the side members 14 so as not to injure the frame. The frame 10 may be passed through the machine by hand or fed therethrough by any mechanical feeding means as desired. After the swatch has been cut it is removed from the frame and a strip of metal or a wire or other reinforcing or attaching strip or member is laid along the center of the binder strip and the swatch folded longitudinally into the shape shown in Figures 4 and 5 with the binder 36 at the top thereof, the reinforcing member enclosed therein with the ends extending as shown in Figure 5, and the severed strands of the yarn 11 forming the body portion of the mop, all of uniform length. One or more lines of stitches are then made in the lower portion of the binding member 36 securely holding the same together and enclosing the reinforcing strip 40 in place. The completed mop is then applied to a mophead of the desired form in any suitable manner.

It will be seen that by this method of manufacture a great saving can be effected both in time and material, as compared to the ordinary method heretofore employed.

By this method of manufacture there is no waste in the making of a mop as the ends thereof are smooth and even, after the same has been constructed as shown in Figure 4, and no trimming is necessary. A great saving of time and labor is also effected as the entire series of operations can be all performed within a very small fraction of the time usually required for the manual assembly of such a mop.

I am aware that many changes may be made in various steps of the process and numerous details of construction of the apparatus varied without departing from the principles of this invention, and I therefore do not purpose limiting the patent granted otherwise than necessitated by the prior art.

I claim as my invention:

1. A method of making mops including winding yarn upon a frame in regular order, attaching the yarn along its central longitudinal line by stitches to a binder, cutting the yarn along the edges of the frame, and folding over the swatch to the form of a mop and again stitching through the binder.

2. A method of making mops including winding yarn upon a frame in regular order, attaching a reinforcing binder transversely of the winding of the yarn along the longi-

tudinal axis of the frame by stitching, cutting the yarn along the edges of the frame, folding the swatch centrally on the binder into the form of a mop, and additionally 5 sewing the binder through the fold to form a loop to retain a reinforcing means.

3. Those steps in the method of manufacturing a mop or the like which include assembling strands of yarn in an orderly relation 10 on a frame, permanently binding them together at their central portions, and subsequently separating the same from the frame so that the ends are of uniform length to form the body of the mop, said separation 15 being accomplished by cutting the strands of yarn at the longitudinal outside edges of the frame.

4. The method of manufacturing a mop or the like which includes assembling strands 20 of yarn in an orderly relation on a frame, binding the strands together along the central longitudinal axis of the frame, and subsequently separating the yarn from the frame in such a manner that the ends are of 25 uniform length and free to form the body of the mop, said separation being accomplished by cutting the strands at the longitudinal outside edges of the frame and finally forming the swatch into a mop by 30 bending the same over at its longitudinal middle portion to form a double thickness, and additionally stitching the binder.

5. The method of manufacturing a mop or the like which includes assembling 35 strands of yarn in an orderly relation on a frame, attaching a binder to the strands

along the longitudinal axis of the frame, and subsequently separating the yarn from the frame so that the ends are free to form the body of the mop, said separation being accomplished by cutting the strands at the longitudinal outside edges of the frame and finally forming the swatch into a mop by bending the same over a reinforcing strip inserted at its longitudinal middle portion, 45 said middle portion being additionally stitched together to retain the reinforcing means.

6. The method of forming a mop which includes assembling a plurality of looped 50 strands of yarn in an evenly spaced relation, binding the same together at their middle portions, severing the loops at their free ends, and assembling the severed ends by bending the strands and the binder on the 55 longitudinal axis of the binder.

7. A method of forming a mop from a single strand of yarn which includes winding the yarn in even layers upon a frame, binding the yarn at its central portions, 60 along the longitudinal axis of the frame, and subsequently severing the yarn at the outer edges of the frame and doubling the swatch so formed along the middle line of the binder. 65

In testimony whereof I have hereunto subscribed my name in the presence of two subscribing witnesses.

WILLIAM SEVERNS.
